US00D998790S

(12) **United States Design Patent** (10) **Patent No.:** **US D998,790 S**
Formica et al. (45) **Date of Patent:** **** Sep. 12, 2023**

(54) **CADDY FOR POSITIVE AIRWAY PRESSURE BREATHING DEVICE**

(71) Applicant: **ResMed Pty Ltd**, Bella Vista (AU)

(72) Inventors: **Justin John Formica**, Sydney (AU);
Max William Andrew Kabilafkas,
Sydney (AU)

(73) Assignee: **ResMed Pty Ltd**, Bella Vista (AU)

(**) Term: **15 Years**

(21) Appl. No.: **29/726,403**

(22) Filed: **Mar. 3, 2020**

Related U.S. Application Data

(60) Continuation of application No. 29/689,342, filed on Apr. 29, 2019, now Pat. No. Des. 880,689, which is a division of application No. 29/601,202, filed on Apr. 20, 2017, now Pat. No. Des. 853,557.

OTHER PUBLICATIONS

Formica et al., U.S. Appl. No. 29/689,342, filed Apr. 29, 2019, entitled "CADDY FOR POSITIVE AIRWAY PRESSURE BREATHING DEVICE," (parent application).

Primary Examiner — Nathan M Johnston

(74) *Attorney, Agent, or Firm* — Nixon & Vanderhye P.C.

(57) **CLAIM**

The ornamental design for a CADDY FOR POSITIVE AIRWAY PRESSURE BREATHING DEVICE, as shown and described.

DESCRIPTION

FIG. 1 is a perspective view of a CADDY FOR POSITIVE AIRWAY PRESSURE BREATHING DEVICE showing a first embodiment of our new design;

FIG. 2 is a reverse perspective view thereof;

FIG. 3 is a right side view thereof;

FIG. 4 is a left side view thereof;

FIG. 5 is a top view thereof;

FIG. 6 is a bottom view thereof;

FIG. 7 is a rear view thereof;

FIG. 8 is a front view thereof;

FIG. 9 is a bottom perspective view thereof;

FIG. 10 is a perspective view of a CADDY FOR POSITIVE AIRWAY PRESSURE BREATHING DEVICE showing a second embodiment of our new design;

FIG. 11 is a reverse perspective view thereof;

FIG. 12 is a right side view thereof;

FIG. 13 is a left side view thereof;

FIG. 14 is a top view thereof;

FIG. 15 is a bottom view thereof;

FIG. 16 is a rear view thereof;

FIG. 17 is a front view thereof; and

FIG. 18 is a bottom perspective view thereof.

The broken lines show portions of the caddy for positive airway pressure breathing device that form no part of the claimed design.
